TOOL FOR PUNCHING METAL ROOFING

Ernest Payne, Denver, Colo.

Application November 5, 1945, Serial No. 626,823

3 Claims. (Cl. 164—119)

1 This invention relates to a tool for punching holes in sheet metal roofing for receiving the roofing nails for attaching same to the supporting sheathing or lathing.

Sheet metal roofing is usually formed in two styles known as "corrugated" and "V-crimp" roofing. The corrugated roofing is rolled to form an alternating series of ridges and troughs rounding into each other. The "V-crimp" roofing has a plurality of relatively sharp ridges running lengthwise of the strip, usually one ridge at each edge and one on the middle line thereof. The edge ridges of adjacent strips are overlapped. The strips are nailed to the sheathing or lathing by means of roofing nails which must be placed along the apex of the ridges to prevent water from entering around the nails. It is exceedingly difficult to drive the nails through the heavier gauges of sheet and it is also difficult to accurately position the nails on the apex of the ridges when being driven since they slip therefrom before piercing the metal.

The principal object of this invention is to provide a punching tool which will easily pierce the heaviest sheet and which can be readily used for placing the nail holes along the apex ridges of the roofing so that the nails may be properly positioned therealong.

Another object of the invention is to provide a punch of this character in which the punch member may be quickly and easily removed for replacement or resharpening purposes.

Other objects and advantages reside in the detail construction of the invention, which is designed for simplicity, economy and efficiency. These will become more apparent from the following description.

In the following detailed description of the invention, reference is had to the accompanying drawing which forms a part hereof. Like numerals refer to like parts in all views of the drawing and throughout the description.

In the drawing:

Fig. 1 is a side elevation of the improved tool as it would appear when being used on a "V-crimp" roofing;

Fig. 2 is a similar view illustrating its use on "corrugated" roofing;

Fig. 3 is an enlarged, longitudinal section through the head of the tool;

Fig. 4 is a cross section therethrough looking down on the line 4—4, Fig. 3;

Fig. 5 is a magnified view of the point of a punch employed in the improved tool;

2 Fig. 6 is a cross section of the point of the punch, taken on the line 6—6, Fig. 5;

Fig. 7 is a bottom view of the improved tool; and

Fig. 8 is a vertical section through an alternate form of the tool.

In Figs. 1 and 2, roof sheathing or lathing is illustrated at 25 for supporting sheet metal roofing. In Fig. 1, typical "V-crimp" metal roofing is indicated at 27 with its overlapping V-ridges at 28. In Fig. 2, typical corrugated metal roofing is indicated at 29.

The preferred form of the improved tool employs a downwardly facing, annular, threaded socket 11. A cup member 12 is threaded upwardly into the socket 11, and a cap 13 is projected upwardly through the top thereof.

The upper portion of the socket 11 is flanged inwardly, as shown at 14, so that it will project into the interior of the cup 12. The cap 13 is provided with a peripheral flange 15 around its bottom which contacts the flange 14 to prevent withdrawal of the cap 13.

The bottom of the cup 12 is formed with a diametrically extending concavity 16 which fits over the apexes of the ridges of the roofing and contacts the sides of said ridges.

A punch guide hole 17 is formed at the center of the concavity for guiding a punch member. The punch member consists of a punch 18 terminating at its top in a flat head 19 which fits snugly within the cap 13. The lower extremity of the punch 18 is sharpened to a piercing point 20. A plurality of laterally extending metal cutting ridges 21 surround the point 20.

The head 19 is constantly urged upwardly into the cap 13 to support the latter by means of a compression spring 22. The lower extremity of the spring 22 fits into a cup washer 23 resting on the bottom of the cup 12, and surrounding the opening 17. A ring band 24 is positioned within the cup 12 to be contacted by the cap 13 to limit the downward movement thereof.

In use, the concavity 16 of the cup 12 is placed over a ridge of the corrugated roofing 29, as shown in Fig. 2, or over the V-ridges 28 of the roofing 27, as shown in Fig. 1. The cap 13 is then struck with a hammer with sufficient force to drive the point 20 of the punch 18 through the roofing so as to form a nail hole therein. The cutting ridges 21 on the point 20 split the sides of the nail hole as the punch member enters therein so that the sides thereof will roll uniformly outward.

Only the tapered point 20 of the punch 18 en-

ters the roofing since downward movement is limited by the flange 15 of the cap engaging the stop ring 24. This prevents the punch from becoming stuck in the hole and allows it to be easily withdrawn by the natural expansion of the spring 22. The stop ring 24 also prevents the cap 13 from being driven sufficiently far downward to allow the socket 11 to be damaged by the hammer. It can be readily seen that the punch may be removed and replaced in the tool by simply unscrewing the cup member 12.

The socket 11 is provided with a pair of peripheral flanges 26 which provide convenient finger grips for lifting the punch. These flanges also provide means for retaining a handle 10 in place, if a handle is desired.

The handle 10 is preferably formed from a metal strap having any desired shape. The strap is wrapped about the socket 11, between the flanges 26 and is clamped thereabout by means of a suitable clamp screw 31.

In Fig. 8, an alternate form of the tool is illustrated which employs the same handle 10 and socket 11 as the previously described form. In this case, however, a split pin and spring socket member 30 is placed within a cap 31 in the socket 11. The two halves of the member 30 enclose a headed punch pin 32 which can be projected through a guide opening 33 in a concave bottom 34 in a cup member 35. A compression spring 36 acts to force the member 30 upwardly and it is driven downwardly by a blow of the hammer on the cap 31 as in the preceding form.

In this form, the bottom of the member 30 strikes the bottom 34 to limit downward movement of the cap 31.

The operation and use of the alternate form are similar to that of the previously described form.

While a specific form of the improvement has been described and illustrated herein, it is desired to be understood that the same may be varied, within the scope of the appended claims, without departing from the spirit of the invention.

Having thus described the invention, what is claimed and desired secured by Letters Patent is:

1. A tool for punching holes in the ridges of sheet metal roofing comprising: a cup member; a concavity in the bottom of said member extending diametrically thereof for receiving the roofing ridges; a punch member within said cup member extending through a guide opening in the bottom thereof at the apex of said concavity; spring means for supporting said punch member, said punch member being adapted to be driven downwardly by the blow from a striking tool; and a

plurality of laterally extending metal cutting ridges positioned around the point of said punch member for splitting the edge of the opening formed thereby.

- 5 2. A tool for punching holes in the ridges of sheet metal roofing comprising: a handle; an annular, downwardly-facing, threaded socket carried at one extremity of said handle; an inverted, cup-shaped cap member extending through a concentric opening in the top of said socket; a peripheral flange about the open face of said cap member preventing its complete passage through said opening; a cup member threaded into said socket and closing the bottom thereof; an upwardly indented, ridge-receiving groove extending diametrically across the bottom of said cup member and provided with a punch opening at its apex; a punch within said cup member extending into said opening; and resilient means 10 supporting and maintaining said punch in contact with said cap.
- 15 3. A tool for punching holes in the ridges of sheet metal roofing comprising: a handle; an annular, downwardly-facing, threaded socket carried at one extremity of said handle; an inverted, cup-shaped cap member extending through a concentric opening in the top of said socket; a peripheral flange about the open face of said cap member preventing its complete passage through said opening; a cup member threaded into said socket and closing the bottom thereof; an upwardly indented, ridge-receiving groove extending diametrically across the bottom of said cup member and provided with a punch opening at its apex; a punch within said cup member extending into said opening; and resilient means 20 supporting and maintaining said punch in contact with said cap.
- 25 4. A tool for punching holes in the ridges of sheet metal roofing comprising: a handle; an annular, downwardly-facing, threaded socket carried at one extremity of said handle; an inverted, cup-shaped cap member extending through a concentric opening in the top of said socket; a peripheral flange about the open face of said cap member preventing its complete passage through said opening; a cup member threaded into said socket and closing the bottom thereof; an upwardly indented, ridge-receiving groove extending diametrically across the bottom of said cup member and provided with a punch opening at its apex; a punch within said cup member extending into said opening; and resilient means 30 supporting and maintaining said punch in contact with said cap.
- 35 5. A tool for punching holes in the ridges of sheet metal roofing comprising: a handle; an annular, downwardly-facing, threaded socket carried at one extremity of said handle; an inverted, cup-shaped cap member extending through a concentric opening in the top of said socket; a peripheral flange about the open face of said cap member preventing its complete passage through said opening; a cup member threaded into said socket and closing the bottom thereof; an upwardly indented, ridge-receiving groove extending diametrically across the bottom of said cup member and provided with a punch opening at its apex; a punch within said cup member extending into said opening; and resilient means 40 supporting and maintaining said punch in contact with said cap; and an annular stop member in said cup in the descending path of said cap to limit the downward movement of the latter.
